UNITED STATES PATENT OFFICE.

JOHN A. PILCHER, OF ROANOKE, VIRGINIA.

CAR-DOOR ARRANGEMENT.

Application filed February 18, 1922. Serial No. 537,461.

To all whom it may concern:

Be it known that I, JOHN A. PILCHER, a citizen of the United States, residing at Roanoke, in the county of Roanoke and 5 State of Virginia, have invented certain new and useful Improvements in Car-Door Arrangements, of which the following is a specification.

This invention relates to a door arrangement for railway cars, and is particularly applicable to the doors of hopper cars where they are arranged in twin fashion. The object of the invention is to provide a door arrangement wherein the door will be effectively sealed in a simple manner so as to prevent loss of lading, particularly when material such as fine coal is to be handled.

With this general and other more specific objects in view, such as the provision of an 20 economical form of door stiffening member and an inexpensive form of hinge arrangement, the invention consists of the formation, combination and arrangement of parts as will be herein described and particularly 25 claimed.

In the accompanying drawings, which illustrate in diagrammatical form a set of doors as applied to a railway car, Figure 1 is a diagrammatical view, in side elevation, 30 of a pair of doors applied to a hopper car. The door to the left in this view is shown as fully closed. The door to the right is shown as partially closed. Figure 2 is a view similar to Figure 1, except that in this 35 view both of the doors are shown as fully closed. Figure 3 is a fragmentary view of a door hinge, the relationship of hinge and hinge pintle in this view coinciding with the positions of the doors shown in 40 Figure 1. It will be noted that the scale of this figure is somewhat enlarged over that of Figure 1 or Figure 2. Figure 4 is a view similar to Figure 3, but showing the relative 45 positions of hinge and hinge pintle corresponding to the position of the doors in Figure 2.

Referring now to these drawings, the car illustrated for showing the present embodiment of the invention is of a type in general use today, wherein a pair of doors 1 and 2 are hinged along their remote edges to the car body as at 3 and 4. The free edges 5 and 6 of the doors are arranged to contact each other when the doors are closed. The

doors may be supported when closed by any 55 suitable means, but preferably the form of door supporting hooks illustrated in Cremean Patent #1,336,134 is made use of. These hooks are denoted in the present drawings by the numerals 7 and 8. Any suitable form of brackets such as 9 and 10 may be used for securing the hooks to the car side, and the customary locking cams such as 11 and 12 may be supplied to retain the hooks in engagement with the doors. The 60 hooks preferably seat beneath the ends of angle iron stiffeners such as 13 and 14 secured to the under faces of the door plates. The supporting points are preferably near the free edges of the doors, and it is also 65 preferable that the doors 1 and 2 shall lie upon inclined planes so that the free edges of the doors when closed are lower than the hinged edges thereof. This is desirable 70 so that the effect of gravity may at all times 75 be utilized to hold the door edges in contact with each other when the car is under load and equipped with the present improvements.

It will be noted that the hinge apertures 80 such as 15, shown more clearly in Figures 3 and 4, are elongated in a direction coincident with the width of the doors, or in other words, these apertures are made of such length as to allow a slight slippage of the 85 doors with respect to the hinge pintles 16 thereof, or with respect to the car body, either toward the hinged edge of the door, or away from the hinged edge of door into 90 contact with the abutting edge of the adjacent door.

It will be noted that when the doors are entirely released from the hooks 7 and 8, both doors 1 and 2 will, upon swinging downward, drop to the extremely downward 95 position allowed by the length of the hinge apertures 15. Upon now raising the free edge of door 1, it will remain in this same extreme hinge position, and even when the locking face of the hook 7 is properly seated 100 beneath the one leg of the angle 13, the door 1 will be at the extreme outward position allowed by the clearance of the hinge pintle in this aperture, the door 1 being shown in this position in Figure 1. It will be noted 105 that upon the application of a suitable force to the free edge of the door 1, as at 5, this door may slip toward the hinged edge of

the same, due to the hinge clearance aforesaid.

When door 2 is now lifted up, it will also be in this extreme hinge position, and the edge 6 thereof will, because of this abnormal displacement contact or slightly overlap the corresponding free edge 5 of the door 1. This contacting of the edge 6 of door 2 with the edge 5 of door 1 is clearly shown in Figure 1. As the free edge of door 2 is now more forcibly lifted, the contacting of the edges 5 and 6 will induce sufficient and suitable forces to cause at least one of the doors, and possibly both of them, to slip 10 toward their respective hinged edges, so that the doors when fully closed will occupy the tightly abutting positions shown in Figure 2.

The form of door supporting device here- 20 tofore noted as especially desirable for use with this type of door allows this slipping movement without any interference from the door supporting mechanism itself.

When the doors are in this closed position, 25 it will be appreciated that the weight of the lading upon the door will constantly tend to hold the doors tightly against each other at 5 and 6, due to the fact that the free edges of the doors are at a lower level than the hinged edges thereof. It will be noted furthermore that the provision for the hooks 30 7 and 8 to swing toward each other and toward the free edges of the doors into locking position will permit the two doors 35 to keep constantly working toward each other as the car vibrates in transit, without any hindrance from the hook mechanism.

The free edges of the doors are turned 40 downward or formed into roll shape for the purpose of causing this slippage of the doors heretofore described. The curved abutting edge of each door thus forms in effect an inclined plane against which the opposite door may react to produce the 45 effects desired. The rolled edges also constitute integral stiffeners for the edges of the doors to prevent buckling of the same.

The door arrangement described provides 50 in a very simple manner an effective means whereby the doors are always held in tight abutment, and when used with a positive securing mechanism such as the hooks shown and identified, provides a door arrangement that offers a maximum of security against 55 loss of lading. The arrangement is entirely inexpensive, as in practice the doors may be constructed in the present manner with practically no additional cost whatsoever.

I have thus described a preferred embodiment of the invention. Other embodiments 60 are contemplated within the scope of the

appended claims without departing from the spirit of the same.

What is claimed is:

1. In a door arrangement for railway 65 cars, a door hinged to the car body, along one of its edges, an abutment arranged for contact with the free edge of the door when the same is in closed position, the door being arranged to slightly over-reach 70 the said abutment when nearly closed and being capable of a slight slippage toward its hinge point upon the application of a sliding force to the free edge of the door, the said abutment and the adjacent edge of the door 75 being so associated that force applied to lift the free edge of the door into fully closed position will produce a resultant slippage force of the character set forth.

2. In a door arrangement for railway cars, 80 a door hinged to the car body, the hinges therefor being arranged to allow a slippage of the door to or from the hinge point thereof, door-supporting means, and an abutment arranged for contact with the free 85 edge of the door, the aforesaid slippage being of sufficient amount and the parts being so arranged as to permit and cause the free edge of the door to overlap the face of the abutment when the door is nearly closed 90 and the entire door to move toward the hinge point of the door as the closing operation is completed.

3. In a door arrangement for railway cars, 95 a pair of doors hinged to the car body with their free edges adjacent and arranged to abut when the doors are closed, means for supporting the free edges of the doors, the said doors being arranged to over-reach each other at their free edges when nearly 100 closed, the door hinges being arranged to allow a slippage of at least one of the doors toward the hinge point thereof upon application of a sliding face to the free edge 105 of the door.

4. In a door arrangement for railway cars, 110 a pair of doors hinged along their remote edges to the car body and with their free edges abutting each other, the hinges for said doors having elongated pintle openings so associated as to permit relative movement of the doors toward or away from each other in response to suitably directed forces applied thereto, the free edges of the doors being arranged to contact each other when the doors are nearly closed, and being so formed and shaped that movement of either door toward fully closed position will cause at least one of the doors to move toward its 115 hinge points.

In testimony whereof I affix my signature.
JOHN A. PILCHER.
